Des. 191,570
Patented Oct. 10, 1961

191,570

PORTABLE ELECTRIC JIG SAW

Walter M. Downs, Towson, Md., assignor to The Black
and Decker Manufacturing Company, Towson, Md.,
a corporation of Maryland

Filed May 26, 1960, Ser. No. 60,746

Term of patent 14 years

(Cl. D93—3)

FIG. 1

FIG. 2

FIG. 3FIG. 4FIG. 5FIG. 1 is a front perspective view of a portable electric jig saw;

FIG. 2 is a rear perspective view thereof, with the saw blade omitted for convenience of illustration;

FIG. 3 is a front elevational view thereof;

FIG. 4 is a rear elevational view thereof; and

FIG. 5 is a top plan view thereof.

The dominant feature of my design resides in the portion shown in full lines.

I claim:

The ornamental design for a portable electric jig saw, as shown and described.
